UNITED STATES PATENT OFFICE

KARL TEICHMANN, OF STUTTGART, WÜRTTEMBERG, GERMANY.

GAS-ENGINE.

SPECIFICATION forming part of Letters Patent No. 269,163, dated December 12, 1882.

Application filed August 14, 1882. (No model.) Patented in England April 28, 1882, No. 2,008; in France April 28, 1882, No. 148,644; in Belgium April 28, 1882, No. 57,745; in Italy April 28, 1882, XVI, 14,148 and XXVIII, 168; in Luxemburg May 1, 1882, No. 198, and in Austria-Hungary July 7, 1882, No. 1,200 and No. 1,202.

To all whom it may concern:

Be it known that I, KARL TEICHMANN, a subject of the Emperor of Germany, and a resident of Stuttgart, Kingdom of Württemberg, Germany, have invented certain Improvements in Gas-Engines, of which the following is a specification.

My invention consists of certain improvements in gas-engines, not only in the general construction of the engine, but also in the devices for regulating the supply of the gas, the slide-valve, devices for insuring the mixture of the gas and air, and the devices for igniting the mixture, as more fully described hereinafter.

In the accompanying drawings, Figure 1, Sheet 1, is a vertical section of a caloric or gas engine constructed in accordance with my invention; Fig. 2, a sectional plan of the same on the line 1 2, Fig. 1; Figs. 3, 4, 5, 6, and 7, Sheet 2, diagrams illustrating different modifications in the general arrangement of the main parts of the engine; Fig. 8, Sheet 3, a face view of the seat for the slide-valve, showing the air, gas, and water ports; Fig. 9, a transverse section of the slide-valve, seat, and ports; Fig. 10, a view of the face of the slide-valve; Figs. 11 and 12, views showing the slide-valve in its two extreme positions; Figs. 13, 14, and 15, sectional views of different forms of gas-igniting devices, and Figs. 16 and 17 views of the cut-off valve for the gas-supply.

The principal parts of the engine are the gas and air mixing chamber B, a pumping or compression cylinder, A, and its piston, and a larger expansion or working cylinder, C, and its piston, and the crank-shaft, rods, and valve-gear. In Figs. 1 and 2 I have shown the compression and expansion cylinders as arranged side by side, and the mixing-chamber immediately underneath the compression cylinder, and the crank-shaft and connecting rods above the cylinders; but it will be understood that the relative arrangements of the several parts may be modified as found convenient without departing from my invention. For instance, in Figs. 3, 4, 5, 6, and 7 I have shown diagrams

illustrating different relative arrangements of the principal parts of the engine, which will be readily understood without further description.

Referring to Figs. 1 and 2, the piston C' of the expansion-cylinder C is connected by the rod C² to the crank-shaft T, the rod C² being connected by the beam T' to the rocking frame T², and the rod A² of the piston A' of the compression-cylinder A is connected to the beam T'. The cylinder C is in communication with the mixing-chamber B through a conduit, B', containing the device for igniting the combustible mixture of air and gas entering said conduit from the chamber B through the outlet-port b', controlled by the slide-valve D, Fig. 1, which also controls the air-inlet passage a, gas-inlet passage d, Fig. 2, and port e, forming the communication between these ports and the interior of the mixing-chamber and the compression-cylinder A.

The construction of the slide-valve D and the arrangement of the ports are illustrated more fully in Figs. 8 to 12, inclusive, in which it will be seen that a cavity, b, in the face of the valve, when the latter is in the position Fig. 12, forms a communication between the air-inlet a and passage c to the compression-chamber, and at the same time the passage e, Fig. 10, in the valve is brought opposite the gas-inlet d, so that the gas will enter a chamber, f, in the rear of the piston, and thence pass through perforations to the cavity b to be drawn with the incoming air into the cylinder C on the rise of the piston in the latter. Unlike the slide-valves of most gas-engines, the valve D has only one bearing-face, instead of moving between two bearing-plates, the valve being maintained in position by the pressure of gas in the chamber B. When the valve D has been moved to the position Fig. 11 the air and gas pass from the cylinder A into the chamber B, which, on the rising of the valve D to the position shown in Fig. 12, can pass out through the outlet-port b' and pipe B' to the interior of the expansion-cylinder C.

In the tube B' is the device F for igniting

the explosive mixture of air and gas. The precise construction of this igniting device may be varied. In Fig. 13, for instance, I have shown a U-shaped pipe, g , the bend of which 5 is heated red-hot by a gas-jet, g' , within the tube. In Fig. 14 I have shown a straight pipe, g , heated by a gas-jet, g' , and having a small tube, h , passing through it, while in Fig. 15 I have shown an igniter like that shown in Fig. 10 10 14, except that a diaphragm, i , is substituted for the tube h .

The products of combustion, after having performed their work, pass out from the cylinder C through the outlet E' , provided with the 15 valve E , which is operated by a toe, E^2 , Fig. 1, from an eccentric on the shaft T.

The slide-valve D is mounted on a rod, D' , passing through a stuffing-box in the bottom of the mixing-chamber B, and having the necessary reciprocating movements imparted to it 20 through the medium of an eccentric on the main shaft T, eccentric-rod, and rock-shaft in any convenient manner.

The inlet-pipe M, Fig. 2, for the supply of 25 gas, is provided with two valves, both controlled by a centrifugal governor on the shaft K—one valve, n , for regulating the supply of gas, and the other, q , for cutting off the gas entirely. The valve n is a disk-valve, Figs. 16 30 and 17, carried by a rotary shaft, m , mounted in bearings in the frame, and carrying at its opposite end a horizontal arm, l' , with a counter-weight, which causes the vertical arm l on the said shaft to press on the end of the movable rod or axis K in the direction of the arrow, Fig. 2, against the centrifugal action of the governor-balls K' , when the shaft is driven from some moving part of the engine, as will be readily understood. Hence when there is 35 40 too great an increase in the speed the governor-rod K will turn the shaft m against the action of the counter-weight, and tend to close the disk-valve n . This disk is not set up close to its seat, however, so that a little gas will 45 pass through at all times, sufficient to make the mixture inflammable, no matter what may be the position of the valve n .

To insure the automatic cut-off of the entire supply of gas, I employ a second valve, q , 50 which is controlled by the connecting-rod r , bell-crank lever p^2 , rod p' , and rock-shaft carrying the arm p . A cam, o , is arranged on the governor-rod K, Fig. 2, so that when the engine is moving at too high a speed the said 55 cam o will come into contact with an arm, p , and through the rods and levers described close the valve q , while when the engine has slowed down again the cam o will move back, and, acting on a second arm on the rock-shaft carrying 60 the arm p , open the valve q again.

In order to prevent the too great cooling of the igniting-pipe F when the gas-supply is cut off and the engine is running with air only, I provide the pipe F with a shield, s , (shown in 65 different forms in Figs. 13 and 14,) which is

turned on its pivot by the arm S, connected to the rod r , Fig. 2, to protect the hottest part of the pipe F from the cold air. The air and gas entering through the separate ports are more or less mixed in passing through the valve D 70 and passage c and cylinder A; but to insure their more thorough mixture I arrange in the chamber B a bent perforated plate, G , which is adjustable horizontally by suitable means (not shown) to vary the space t between the 75 plate G and the valve D, and that u between the edge of the plate and the wall of the chamber B, Figs. 1 and 2. The perforations may also be provided with devices for closing them.

In order to keep the compression-cylinder 80 and mixing-chamber cool, I arrange a water-jacket around both and a water-space between the two, as shown in Fig. 1, and in the seat for the slide-valve D, I arrange two water-ports, y , Fig. 8, which communicate with grooves x 85 in the face of the slide-valve, Fig. 10, and a water-space, v , Fig. 9, in the body of the valve, so as to allow of a circulation of water through the latter to keep it cool at all times, in no matter what position the valve may be. 90

When the engine is in operation it will be seen that the two pistons A' and C' both move in the same direction at the same time, and when the two pistons are rising the valve D is in such a position, Fig. 12, as to allow the mixture of air and gas to be drawn into the cylinder. The slide then begins to descend just before the piston A', so as to close the port c , Fig. 9, and allow the piston A' to compress the air and gas, which, on the further descent 100 of the slide D to open the port c , Fig. 11, pass into the chamber B, and thence on the next rising movement of the valve D, Fig. 12, and of the piston C', the gaseous mixture is drawn into the cylinder C, being ignited by the red-hot pipe g on its passage through the tube B'. The valve E is opened just before the piston C' begins its descent, so as to allow of the escape 105 of the products of combustion.

I claim as my invention—

1. A gas-engine having a compression-cylinder, an expansion-cylinder, an intermediate mixing-chamber, and a pipe forming a communication between the mixing-chamber and expansion-cylinder, and provided with an igniting device, all substantially as set forth. 115

2. In a gas-engine, the combination of a jacked compression-cylinder and a mixing-chamber with an intervening water-space between the two. 120

3. The combination of the expansion-cylinder and the mixing-chamber of a gas-engine with a tube or conduit, B', forming the communication between the two, and a pipe or pipes, g , heated internally within said tube B', 125 substantially as described.

4. A gas-engine having a mixing-chamber containing a perforated distributing-plate, G.

5. The combination of the gas-supply pipe of a gas-engine with two valves, n and q , both 130

controlled by a governor—one to regulate the supply of gas and the other to cut it off.

6. The combination of a gas-engine with an igniting device consisting of a pipe or pipes heated internally, with an adjustable shield, *s*, controlled by the valve-gear, substantially as and for the purpose set forth.

7. The combination of a slide-valve having a water-space, *v*, with a valve-seat having spaces

communicating at all times with the space in front of the valve, substantially as specified.

In testimony whereof I have signed my name to this specification in the presence of two subscribing witnesses.

KARL TEICHMANN.
